UNITED STATES PATENT OFFICE.

FRANCIS MARION SNYDER, OF MANSFIELD, OHIO.

MEANS FOR COUPLING AND UNCOUPLING RELATIVELY MOVABLE MEMBERS OF MACHINES.

1,382,131.

Specification of Letters Patent. Patented June 21, 1921.

Application filed June 19, 1920. Serial No. 390,230.

To all whom it may concern:

Be it known that I, FRANCIS MARION SNYDER, a citizen of the United States of America, residing at Mansfield, in the county of Richland and State of Ohio, have invented certain new and useful Improvements in Means for Coupling and Uncoupling Relatively Movable Members of Machines, of which the following is a specification.

This invention relates to a coupling mechanism and is especially adapted for coupling the walking beam of well drilling machines to the crank of the band wheel shaft.

It is well known to those skilled in the art of drilling for water, oil, gas or for other purposes that in operating the drilling tool it is necessary to provide a clamping means for clamping to the rope to which the drill and other appliances are attached which clamping means must be adjustable on the rope at different positions for the purpose of drilling deeper into the soil when desired.

In the use and operation of well drilling machines the customary and conventional manner of operating same is to disconnect and remove the pitman from the walking beam and crank pin of the band wheel shaft thereby permitting the walking beam to idle while the clamping means on the rope is being adjusted by the operator.

It is obvious that in disconnecting or connecting the conventional type of pitman to the elements referred to that it requires considerable labor and time; that during the time such changes are being made no drilling is being performed resulting in loss of efficiency and increasing the expense and labor of drilling.

It is further well known to those skilled in the art of the operation of drilling machines that in order to disconnect the pitman from the crank pin of the band wheel shaft of the conventional type of well drilling machines that the connections of the pitman to the crank pin and walking beam must be fitted so as to leave considerable lost motion between the connecting parts to permit the pitman to be moved laterally in the operation of withdrawing the pitman from its connection to the crank pin of the band wheel shaft which results in permitting the parts to pound and vibrate with resultant loss of efficiency in the operation of the well drilling machine.

One of the objects therefore of the present invention is to provide means of coupling and connecting the walking beam and crank pin of the band wheel shaft by means of a pitman which can be closely fitted to the connecting parts thereby obviating the lost motion incident to the loose connections referred to.

Another object is to provide means of coupling and uncoupling the pitman conveniently and expeditiously from the walking beam by the manipulation of a cable attached to the said mechanism by exerting a pull thereon.

A further object is to provide means of maintaining the pitman in a predetermined position and in alinement with the bearing provided in the walking beam when the pitman is in uncoupled position.

These and other objects are attained by the mechanism illustrated in the accompanying drawings in which:

Figure 1 is a side elevation of a portion of a drilling machine showing the pitman coupled or connected to the walking beam thereof.

Fig. 2 is a top view of the walking beam having mounted thereon a slideable coupling member.

Fig. 3 is a side elevation of a portion of a drilling machine showing the walking beam disconnected or uncoupled from the pitman with a portion of the framework of the derrick omitted to more clearly show its operation.

Fig. 4 is an end elevation of the pitman showing a yoke attached thereto with a horizontal shaft journaled thereon.

In the drawings the invention is shown applied to a well drilling machine as it is especially adapted to be used in combination therewith. It is obvious, however, that the invention can be used with equal efficiency where it is desirable to uncouple or couple one end of a pitman from or to a walking beam or the like, to permit the walking beam to idle, or for operation as desired.

In the drawings reference numerals 1, 2, 3 and 4 indicate the framework of an ordinary portable well drilling machine which is mounted on wheels 5 carried by a hanger 6. The band wheel shaft 7 of the drilling machine is provided with the usual crank 8 and the shaft is journaled in boxes 9. A band wheel 10 is mounted upon the band

wheel shaft 7 receiving power to rotate the shaft from any source of supply through the medium of the belt 11. A drum 12 is provided for the drill rope 13. The drill rope 5 is wound around the drum 12 at one end and its opposite end passes over the periphery of the sheave pulley 14. The downwardly extending portion 15 of the drill rope 13 is guided by the walking beam through the 10 medium of the slot 16. The drill 17 is attached to the drill rope in the conventional manner. The sheave pulley 14 as shown in the drawings is preferably mounted adjacent to the upper end of the derrick 18. 15 The mechanism hereinbefore described is of the ordinary and conventional form therefore no claim is made to the elements described or combinations thereof. In applying the elements of the present invention and combinations thereof to the parts above described and combining said elements with others herein-after described to carry out the objects of the present invention a pitman 19 is provided having one end attached to the crank 20 pin 20 of the crank 8. The free end of the pitman is preferably provided with bars 21 and 22 which are fastened to the end of the pitman 19 and curved to provide a yoke 23 as shown in Fig. 4. A shaft 24 is journaled to the upper portion of the yoke and its ends 25 and 26 extend beyond the sides of the yoke as shown in Fig. 4. A shaft 27 is journaled to the derrick 18 and a walking beam 28 is pivotally secured thereto for 30 oscillation by a journal bearing 29. A base block member 30 having an open bearing 31 provided thereon is fitted to one end of the walking beam and is securely fastened thereto by any well known fastening means 35 such as bolts 32 or the like. 40

A sliding member 33 having an inclined portion or cam 34 formed on its end is mounted upon the member 30 and is adapted to be slidably operated thereon. The 45 sliding member 33 is provided with slots 35 to receive bolts 36 to guide the sliding member 33 when the same is operated for the purpose intended. The heads of the bolts 36 are adapted to be adjusted in close contact in the top of the sliding member to prevent same from being displaced when the sliding member is operated.

The cross bar 37 of the sliding member 33 has one end of a coil spring 38 attached 55 thereto and its opposite end is attached to a pin 39 which is secured to the member 30 in such a manner as to exert a tension of the spring to force the end of the sliding member to normally cover the opening in the bearing 31. In other words the tension of the spring 38 is exerted to force the end of the sliding plate to cover the open portion of the bearing 31 when the pitman is 60 connected to the walking beam for performing the operation of drilling.

It will be understood by those who are skilled in the art that an adjustable clamping means 40 is provided and adapted to be clamped to the downwardly extending portion 15 of the drill rope 13 at different positions or elevations. As the drill bores deeper into the soil the clamping mechanism 40 must be adjusted to leave a predetermined amount of rope between the clamping mechanism and the end of the drill. 75

It will be further understood by those skilled in the art that an adjustment of the clamping means 40 at regular intervals (usually about one-half hour apart) must be made and that during the adjustment of 80 said clamping means on the drill rope that the drill rope must idle. It is also necessary in the use of the conventional type of connections between the walking beam and crank pin of the band wheel shaft to disconnect the pitman from the crank pin to permit the walking beam to idle thereby making it necessary to perform considerable labor and resulting in considerable loss of time that would otherwise be employed in 85 drilling if means were employed to disconnect and connect the pitman and walking beam automatically and instantly by the operator by actuating the mechanism such as shown in the present invention. 95

In the present invention to impart movement to the sliding member 33 to disconnect the walking beam from the shaft 24 the following mechanism is employed: A bracket 41 is provided and a sheave pulley 100 42 journaled thereon as shown in Fig. 2. A cable 43 is attached at one end to a cross bar 37 leaving its free end 44 positioned in close proximity to the operator. When a pull is exerted (assuming that the clamp 40 105 has been released from the drill rope 13) upon the end of the cable 44 the spring 38 is stretched and the end of the sliding member 33 move to uncover the open portion of the bearing 31 thereby automatically and 110 instantly disconnecting the shaft 24 carried by the yoke 23 from the pitman 19. The weight of the base block member 30 is made to overbalance the opposite end of the walking beam, clamping means and connections. 115

In order to maintain at all times the yoke of the pitman and shaft 24 in direct alignment with the open bearing 31 provided in the base block member, bars 45 and 46 120 are pivotally connected to the shaft 27 and to the extending ends of the shaft 24 in the same radius as the walking beam is connected to the shaft 27 with respect to the open portion of the bearing 31. 125

It will be observed that when the operator exerts a pull upon the temper screw the walking beam will be oscillated and the opening to the bearing 31 formed in the walking beam will engage and couple to the horizon- 130

tal shaft 24 of the pitman. As the walking beam is oscillated for the purpose of coupling same to the shaft 24, the inclined end 34 of the sliding member is forced to contact with the shaft 24 and by impact or pressure between the parts movement is imparted to the sliding member 33 thereby uncovering the opening provided to the bearing 31 to permit access of the shaft 24 there-
to for coupling purposes, the sliding member 33 being automatically forced by the tension of the spring to its normal coupling position covering the opening in the bearing 31 and shaft 24.

15 When the walking beam 28 is disconnected or uncoupled from the shaft 24 the walking beam pivots by gravity to the position shown in Fig. 3 which is the most desirable and preferable idle position for the beam to be maintained in while the adjustment of the clamping means on the rope is being made.

In order to maintain the beam in the position shown a pin 47 is secured to the walking beam and a latch 48 is secured to the derrick in alinement with the pin 47 to yieldingly connect with and hold the walking beam when the walking beam is uncoupled from the shaft 24 of the pitman. A spring 48' maintains the latch 48 in normal position. When it is desired to release the walking beam preparatory to coupling same to the shaft 24 of the pitman for operation a pull is exerted on the cable 49 forcing the latch 48 to pivot thereby causing the beam to become released from the latch 48.

Reference numeral 50 represents the bailer and 51 the bailer rope.

It will be observed that the operator of a well drilling machine equipped with the coupling mechanism herein described can couple or uncouple the walking beam from the pitman instantly by simply exerting a pull on the cables or the like hereinbefore described which results in greater efficiency in the operation of drilling on account of the saving of time and labor lost in disconnecting and connecting the conventional pitman from the walking beam to permit the walking beam and drill rope to idle while adjusting the clamping means on the drill rope.

Attention is called to the fact that in the present invention the pitman is disconnected from the walking beam and its weight is supported for coupling purposes by the crank pin of the band wheel thereby relieving the walking beam of the extra weight of the pitman which is incident to the present practice of disconnecting the pitman from the crank pin of the conventional type of drilling machines for the purpose of maintaining the walking beam in idle position.

In supporting the pitman by the crank pin of the band wheel shaft instead of by the walking beam for idling purposes as de-

scribed a deeper hole can be bored in the soil quicker, with less labor and fewer workmen than by drilling machines of the same size which are not equipped with the coupling mechanism of the present invention because the walking beam can be manipulated or lifted to coupling position by the operator with less exertion or labor on account of the fact that the weight of the pitman is supported by the crank pin of the band wheel shaft instead of being supported by the walking beam as is the case in the use of a conventional type of drilling machines.

I claim:

1. In combination, a walking beam, a crank shaft, a crank pin secured to the crank, a pitman secured to the crank pin at one end, a yoke provided on its opposite end, a shaft secured to said yoke, a base block member provided with an open bearing for the yoke shaft secured to the walking beam, and a slidable member mounted upon said base block member normally covering the open portion of the bearing.

2. In combination, a walking beam, a crank shaft, a crank pin secured to the crank, a pitman secured to the crank pin at one end and its opposite end being provided with a yoke, a shaft secured to said yoke, a base block member provided with an open bearing for the yoke shaft and secured to the walking beam, a slidable member mounted upon said base block member normally covering the open portion of the bearing and means for imparting movement to the slid-
able plate to uncouple or couple the walking beam and pitman.

3. In combination, a walking beam, a crank shaft, a crank pin secured to the crank, a pitman secured to the crank pin at one end and its opposite end being provided with a yoke, a shaft secured to said yoke, a base block member provided with an open bearing for the yoke shaft and secured to the walking beam, a slidable member mounted upon said base block member normally covering the open portion of the bearing, means for imparting movement to the slidable member to uncouple or couple the walking beam and pitman and means to maintain the pitman in alinement with the bearing formed in the base block member.

4. In combination, a walking beam provided with an open bearing, a pitman, a yoke provided with a shaft attached to the pitman and means to connect or disconnect the shaft to or from the walking beam.

5. In combination, a walking beam provided with an open bearing, a pitman, a yoke provided with a shaft attached to said pitman, a slidable member mounted on one end of the beam and means to operate the sliding member to force it to cover or uncover the open bearing in the walking beam.

6. In combination, a walking beam, means

to slightly over-balance one end of the beam which is provided with an open bearing and mounted upon one end of the beam and means associated with the last mentioned 5 means which is adapted when movement is imparted to it to cover or uncover said open bearing.

7. In a drilling machine a walking beam, a pitman provided with a yoke, a shaft journaled thereon, a block having an open bearing mounted upon one end of the walking beam; said shaft and open bearing being adapted to engage each other, and means to couple the shaft to the walking beam.

15 8. In a drilling machine, a walking beam, pitman provided with a yoke, a shaft journaled thereon, a block having an open bearing mounted upon end of the walking beam; said shaft and open bearing being adapted 20 to engage each other, and means to couple the shaft to the walking beam, and uncouple the shaft from the walking beam.

9. In combination, a walking beam, a block having an open bearing secured to one end

of the walking beam and of such gravity as 25 to over-balance one end of the beam, a pitman provided with a yoke and a shaft, and means to couple and uncouple the shaft to or from the walking beam.

10. In a drilling machine, a walking beam, 30 a pitman, means to connect or disconnect the pitman from the walking beam, and a block secured to one end of the walking beam of such weight as to over-balance the beam which is also provided with an open 35 bearing.

11. In a drilling machine a walking beam, a pitman, means to connect or disconnect the pitman, a block secured to one end of the walking beam adapted to over-balance the 40 walking beam at one end, and means to automatically maintain the pitman at a pre-determined position after the actuation of the uncoupling means to uncouple the beam from the pitman.

45 In testimony whereof I affix my signature.

FRANCIS MARION SNYDER.
